DESIGN FOR AN ENDPIECE FOR FLUORESCENT LIGHTING FIXTURES

Jerome H. Steinberg, Brooklyn, N. Y.

Application August 17, 1946, Serial No. 132,616

Term of patent 3½ years

(Cl. D48—23)

To all whom it may concern:

Be it known that I, Jerome H. Steinberg, a citizen of the United States, residing at Brooklyn, in the county of Kings and State of New York, have invented a new, original, and ornamental Design for an Endpiece for Fluorescent Lighting Fixtures, of which the following is a specification, reference being had to the accompanying drawing, forming part thereof.

In the drawing:

Fig. 1 is a top view of an endpiece for fluorescent lighting fixtures showing my new design; and

Fig. 2 is an elevational front view thereof.

I claim:

The ornamental design for an endpiece for fluo-

rescent lighting fixtures, substantially as shown.
JEROME H. STEINBERG.
